BINDER

Wilfrid Wedgwood Bowen, Washington, D. C.

Application August 12, 1933, Serial No. 684,912

7 Claims. (Cl. 129—41)

My invention contemplates an improved form of flexible binding post for loose leaf binders and the like.

An object of my invention is to provide such a binding post that will be of a highly flexible nature yet will have sufficient rigidity to prevent the buckling of the post.

A further object is to provide such a post as is suitable for connecting two parallel clamping bars near their ends in a manner obviating the necessity for punching holes through the pages for the reception of the post.

A further object is to provide such a post as will have strength capable of maintaining a tension between the two clamping bars sufficient to retain sheets within the binder solely by means of a clamping force.

A further object is to provide such a post that is capable of being retracted within one, or both, of the two parallel clamping bars in a manner allowing the two covers of the binder to maintain at all times a parallel relationship, one with the other, thus permitting the binder to be stacked on a shelf in the manner of an ordinary bound book.

A further object is to provide such a post as is capable of being protruded from its housing for enough of its length to permit the accommodation in the binder of a greater number of sheets than is usual in binders, already in common use, wherein the pages are retained solely by the clamping action of two parallel bars.

A further object is to provide such a post that will be capable of forming a semi-circle when the binder is fully expanded, thus enabling punctured sheets, through which the post passes to lie flat upon the opened covers.

A further object is to provide such a post as will be composed of a stranded flexible post, or of a chain, covered by a flexible casing.

A further object is to provide such a post in which the flexible casing is composed of a coiled wire or the like, in any event, a casing formed of a single strip of tightly coiled material.

A further object is to provide such a post as will be readily adaptable to all forms of binders in which a post is used.

A further object is to provide novel forms of binders to which my post is peculiarly adapted.

Other objects and advantages reside in the particular structure, combination and arrangement of the various parts, and in certain modes of operation and will be readily apparent to those skilled in the art upon reference to the detailed

description and drawings forming a part of this specification.

In the drawings:

Figure 1 is a detail perspective view of one form of my invention with portions broken away and portions in section;

Figure 2 is an enlarged section of one end of the form of invention shown in Figure 1 and is taken on the line 2—2 of that figure;

Figure 3 is a detail of one end of my binder showing an optional method and means for holding folded sheets therein;

Figure 4 is an enlarged detail of one end of one of the folded sheet retainers shown in Figure 3;

Figure 5 is a view similar to Figure 1 showing a modification of my invention;

Figure 6 is a sectional detail on the line 6—6 of Figure 5;

Figure 7 is a perspective detail of one corner of the form of the invention seen in Figure 5.

With further reference to the drawings, wherein like reference characters have been used throughout to indicate like parts, B indicates a binder having cover plates 1 hingedly connected as at 3 to hollow housings or clamping bars 5 and 7. Sheets or pamphlets 11 are enclosed by a supplemental cover 9 and are clamped between housings 5 and 7 by the binding posts 13. While I have shown the use of a supplemental cover 9 in this form of the invention, such a cover is not essential to the proper operation of my binder and may be omitted if desired. While this form of the invention uses a pair of binding posts 13, it will be sufficient to describe but a single one of them, as each is a duplicate of the other.

The binding post 13 comprises a stranded core 15 and while either wire or cord may be used to make up the core it is desirable, though not essential, that the core be formed of stranded material for it is only in such cores that the desired amount of flexibility together with durability is found. One end of the core 15 is anchored to the housing 7 by being attached to the pierced end 18 of an anchor 17 which is seated within the housing 7 adjacent one end. The other end of the core 15 extends through an opening 12 adjacent one end of the housing 5 and is therein secured to a portion 19 of an internally threaded traveler 20.

A flexible casing 14, composed of a tightly coiled wire or strip, surrounds the core 15 and has one end seated against but not necessarily attached to the housing 7 and the other end similarly seated against the portion 19 of the traveler 20. While

I am aware that prior inventors have formed binding posts by enclosing a stranded core in a flexible casing, none of them have attained the high degree of flexibility that I attain by enclosing my core in a casing composed of a tightly coiled wire or strip. While to all appearances my casing is a coiled spring, and in practice may actually be a coiled spring, it is to be understood that it does not perform the normal function of a coiled spring since there is no tension nor stretch involved,—each coil remaining constantly in contact with the adjoining coils, at least over parts of their lengths. While there is no necessity to use a resilient material for this casing, there is, nevertheless, an advantage in so doing since a coil made of non-resilient substances would tend to lose its original form, whereas, a resilient coil holds its shape and tends to straighten out of its own accord when released from a bending pressure.

The travelers 20 are threadedly mounted on either end of a rod 30, one end 33 of which is rotatably mounted in the casing 5 adjacent one end. One half of the rod 30 is threaded in one direction as at 31 and the other half is threaded in the opposite direction as at 32 so that rotation of the rod 30 in either direction will cause the travelers 20 to move along the rod in opposite directions. Rotation of the rod is accomplished by means of a finger piece 34 which is slidably mounted on the flattened end 35 of the rod 30. While I have shown a pin and slot connection between the finger piece 34 and the flattened end 35, it is obvious that rotation of the rod 30 may be accomplished by any other suitable means.

In operation, pamphlets or sheets are placed between the housings 5 and 7 and the rod 30 is rotated in a direction to cause the travelers 20 to move towards each other. As the flexible cords 15 are attached to the travelers and the housing 7 they tend to pull the latter towards the housing 5 until the sheets are securely clamped between the two. The casing 14 being of a highly flexible character readily follows along behind the travelers 20 as they move together and the clamping operation takes place. The high degree of flexibility of the casing 14 enables the operator to clamp the sheets with the maximum degree of tightness, without providing special guideways for the casing 14. In the prior art I am aware that flexible cords have been enclosed in flexible housings but in every instance where the casing is composed of members linked together or merely composed of members loosely strung on a cord, there is a point between the joints of each link when the right angle turn into the housing is made where inflexibility occurs and the operator must loosen or tighten his grip until a link joint is on the corner. Prior exponents of this art have tried to obviate this evil by forming their casings of rubber or leather or by building guideways into the housings. The former is objectionable as it quickly rots or wears out and the latter is not advantageous because it involves too much expense in the construction of the housing.

My device has successfully eliminated this evil by providing a casing capable of turning at right angles (Figure 2) without necessitating the use of a specially designed guideway,—while at the same time it allows the amount of tension to be adjusted to any desired degree. The casing 14 is formed of metal and it is naturally assumed that it will be strong and extremely durable. By

forming my casing of a coil all of the advantages of a solid walled casing and of a segmented structure are obtained with none of the disadvantages.

The coiled casings 14, as formed, have sufficient rigidity to pass freely through the openings 12 without themselves buckling when the rod 30 is rotated in a reverse direction to loosen the clamping grip of the housings 5 and 7.

The casing 14, by virtue of its coiled structure, lengthens slightly when bent, but returns to a definite minimum length when straightened. In constructing my binding post care is taken that the length of the flexible core 15 is equal to the length of the casing 14 when the latter is bent at a right angle at one point. It will be readily apparent, therefore, that the casing, because its ends are seated upon parts to which the core is anchored cannot expand further in length, and, therefore, is incapable of bending at right angles at more than a single point. Furthermore, the equality in length of the core and casing when bent at one point compels the remainder of the casing to assume a rigid, rod-like form. This property is essential to the successful operation of the binder, since this rod-like rigidity is used to transmit the pushing force exerted by the traveler 20 when it is moved towards the end of the rod 30 when rotated in one direction, and so to force the two clamping bars 5 and 7 apart.

In this form of the invention it is to be noted that the sheets or pamphlets gripped need not be perforated or notched but are held purely by the clamping action of the housings. However, I have found that when a large number of pamphlets or folded sheets are to be clamped,—say enough to form a book 2 inches thick, it is desirable to employ fold engaging hooked bars 40 (Figures 3 and 4). Here it is readily seen that thin strips of metal compose the bars 40 and that each end of the strips are given a right angle twist and bent into a hooked end 41. These hooked ends are hooked over the portions of the casings 14 that connect the housings 5 and 7 and connect the two posts as is readily apparent in Figure 3. As the body of the strips 40 lies between the folds of the sheets or pamphlets the latter are safely and irremovably held in the binder, without the need of great clamping force, thus allowing a maximum of flexibility in the binder.

Figures 5, 6 and 7 illustrate my invention as used with a slightly modified form of binder. In this form each housing 5 and 7 contains a rod 53 and 53^a respectively. About two thirds of each rod is threaded in one direction as at 55 and 55^a,—the other and shorter end having threads running in the opposite direction as indicated at 54 and 54^a (not shown) in the housings 5 and 7. Each longer portion 55 and 55^a of the rods 53 and 53^a carries two spaced carriers 51 and 50 and 51^a and 50^a (not shown) respectively which are designed to travel in the same direction while maintaining their spaced relation when the rods are rotated. The carriers have shoulder portions 57, and 57^a to which are attached the stranded cores 15 and against which rest the ends of the coil casings 14. Carriers 52 (shown) and 52^a (not shown) are carried by the oppositely threaded shorter portions 54 and 54^a (not shown) of the rods 53 and 53^a and they in turn carry binding posts in the same manner as described above.

Thus, it will be seen that in this form of the invention the binding posts are not fixedly anchored in either housing and that by rotating

the finger pieces 56 and 56^a both covers can be extended or contracted at the same time. Similarly, by rotating but one of the finger pieces, the device will operate exactly the same as in the 5 first described form (Figures 1 and 2).

Figure 7 shows a manner in which the finger pieces 56 and 56^a, or for that matter the one 34 of Figures 1 and 2, may be seated in the housings 5 and 7. Openings 58 and 58^a, crescent-shaped 10 in section and open as at 59 and 59^a between the horns of the crescents are formed in one pair of ends of the housings. By means of the openings 59 and 59^a the finger pieces 56 and 56^a,—which are exactly the same as the finger piece 34, (Figures 1 and 2) may be engaged by the fingers and slid outwardly to the operative positions.

By having a threaded rod in each housing 5 and 7, I am enabled to form a binder capable of holding approximately one sixth more pages than 20 the binder shown in Figures 1 and 2. It is also seen that this form of the invention is designed to be used with sheets having notched leaves.

While I have shown and described what I believe to be the preferred forms of my invention, it 25 is to be understood that it is capable of other expressions and embodiments without departing from the spirit of the invention or scope of the appended claims.

Having thus described my invention, I claim:

30 1. A loose leaf binder comprising a pair of opposed covers, a hollow housing along one edge of each cover, a pair of binding post anchors carried by one of said housings adjacent the ends and having binding post attaching means extending therethrough, a pair of binder post openings in said other housing opposite said anchors, a rod longitudinally and rotatably mounted in said other housing, the end portions of said rod being oppositely threaded and threadedly mounting 35 carriers thereon for movement in opposite directions when said rod is rotated, portions of said carriers being adapted for binding post attaching means, and a pair of binding posts for said binder each comprising a flexible core having 40 one end attached to one of said anchors and the other extending through one of said openings and attached to one of said carriers, flexible casings for said cores comprising a tightly coiled strip loosely mounted on each core, and said 45 casings each having one end compressed against a carrier and the other against the opposed housing whereby said casings constitute push elements for separating said housings when the carriers are operated in predetermined directions substantially as described.

50 2. A loose leaf binder of the parallel bar clamping type comprising a pair of opposed covers, a hollow clamping bar formed along one edge of each cover, binding posts fixedly mounted in the 55 end portions of one bar, threaded binding post tightening means carried by the other bar, each of said binding posts comprising a flexible stranded core having one end attached to the first bar and the other to said tightening means and a flexible casing comprising a tightly coiled strip loosely mounted on said core, and said casings each having one end compressed against said tightening means and the other end against the opposed clamping bar whereby said casings constitute

push elements for separating said clamping bars when the tightening means is operated in reverse.

3. A loose leaf binder of the type adapted for use with notched leaves and comprising a pair of opposed covers, a hollow clamping bar formed along one edge of each cover, threaded rods rotatably carried within each bar and longitudinally thereof, a plurality of carriers threadedly mounted on each of said rods, binding posts comprising flexible stranded cores having their opposite ends attached to carriers in opposite bars, flexible casings for said cores, said casings comprising tightly coiled strips loosely mounted on said cores, and having at each end loose abutting engagement respectively with the carriers, and 10 said binding posts, carriers, and rods comprising means for tightening or loosening the clamping relationship of said bars to said leaves.

4. In a loose leaf binder having opposed side clamps, a connecting post for said clamps, comprising a highly flexible core connected at one end to one clamp, a flexible casing comprising a tightly coiled strip loosely mounted on said core and having one end arranged in abutting relation to said aforementioned clamp, a reversibly movable member carried by said other clamp and having a pull connection with the second end of said flexible core for tightening said 20 clamps, and a shoulder on said reversibly movable member arranged to engage the second 25 end of said casing for actuating its first-mentioned end against the first-mentioned clamp for spreading the clamps apart.

5. In a loose leaf binder or the like having a pair of opposed clamps, a reversibly movable 30 member carried by one clamp, a binding post comprising a pull connection between said member and the other clamp for drawing said clamps together when said member is operated in one direction, a coil spring housing for said pull 35 connection tightly compressed between said reversibly movable member and second-mentioned clamp whereby to provide a combined binding post and push connection for separating said clamp when said member is operated in the other 40 direction.

6. In an expandible binder a pair of clamp members, a flexible pull member therebetween, anchor means for one end of the pull member carried by one clamp member, a reversibly movable operating element carried by the other clamp member and having a connection with the other end of said pull member, and a flexible push member concentrically surrounding said pull member in operative engagement with said anchor means 50 and operating element.

7. In an expandible binder, a pair of clamp members, a flexible cable headed in one member and extending into the other, actuator means in said other clamp member to pull said cable for constricting movement of said clamp members, a flexible convolute walled casing loosely surrounding said cable entirely between said actuator means and the clamp member in which the cable is headed, and said actuator means being 60 reversibly operable to push on said casing for expanding movement of the clamp members.
